SWIFT SPOKE GRIPPING DEVICE FOR
SKEIN SUPPORTS

Morris W. Becker, New York, N. Y.

Application August 19, 1941, Serial No. 407,407

10 Claims. (Cl. 242—114)

The present invention is adaptable for use with supports on which a skein of yarn is mounted onto a swift; said swift being of the type comprising a hub having two spaced series of radially extending spokes or arms set opposite in pairs; each such pair being bridged by a skein support, and more particularly this invention relates to means for attaching the skein supports to the spokes of the swift.

The principal object of this invention is to provide a novel and improved means for securely positioning the skein support anywhere along a pair of spokes whereby all slipping is prevented and the spokes are not marred, and which will aid to maintain the skein in taut condition during the unwinding operation.

Another object hereof is to provide a novel and improved article of the character mentioned whereby the position of the skein support on the swift can be easily adjusted in order to adapt the swift to receive skeins of various sized perimeters and to take up any undue slack in the skein.

A further object is to provide an article of the type described which is cheap to manufacture, easy to use, adaptable on existing swifts, and efficient in carrying out the purposes for which it is designed.

Other objects and advantages will become apparent as this disclosure proceeds.

In the accompanying drawing forming part of this application, similar characters of reference indicate corresponding parts in all the views.

Fig. 1 is a diagrammatic perspective view of a swift provided with skein supports and the swift spoke gripping devices for mounting said supports which is the subject of this invention.

Fig. 2 is a perspective view of a skein support provided with spoke gripping devices constructed in accordance with the teachings of this invention. Said gripping devices are here shown in condition free to be manually slid along the spokes of the swift.

Fig. 3 shows an element employed in the embodiment of this invention illustrated in Fig. 2.

Figs. 4 and 5 show intermediate steps in assembling the spoke gripping device, which is one manner of practicing this invention.

Fig. 6 is a view similar to Fig. 2, showing in fragmentary form, and in section, a skein mounted onto the swift in tension, whereby the gripping devices are operated to secure their station on the spokes.

In the drawing, the numeral 15 indicates generally a swift or reel comprised of a hub 16, hav-

ing two spaced series of spokes or arms 17 and 18, extending substantially opposite one another radially therefrom. Each pair of spokes 17 and 18, are bridged by a skein support designated generally by the numeral 19; the ends of such skein supports being provided with spoke engagement means moveable along the respective spokes in order to adjust the effective perimeter of the swift to receive various sized skeins thereon over said skein supports 19. Said attachment or spoke gripping means is in each instance indicated generally by the numeral 20.

In the preferred embodiment herein illustrated, the tubular members 21, are of rubber or other suitable elastic substance, the bore 21' of which is of such dimension as to permit easy sliding of the members 21, by hand, along the respective spokes 17 and 18, on which they are mounted as shown. Each of the members 21 is provided with a hole 21'' through their walls, which holes may be mid-way the height of said members. The component 22, which may be of either elastic or non-elastic material, is mounted one onto each of the tubular members 21, whereby element 22' thereof encircles the body of said member, and element 22'' thereof is passed through the hole 21'' into the interior of said tubular member 21, and up and out through the top opening of the bore 21' and extending from said opening. Such extending ends may in any suitable manner be joined or associated to provide a skein support or bridge across the spokes. In the embodiment illustrated, a skein support construction is employed to follow in the teachings of my previous invention in skein supports for swifts, identified by my Patent No. 2,267,071 issued Dec. 23, 1941. I therefore provide the ends of components 22, with a head 22''', and use a rigid member 23 to complete the bridge; said member 23 having holes 23' for connection purposes as illustrated.

In operation, each of the pairs of spokes 17 and 18 is fitted as shown in Figs. 1 and 2, with the skein supports 19 at substantially equal distances from the axis of the hub 16, so that the effective perimeter of the swift so set up, shall exceed the actual perimeter of the skein 26, which is to be mounted for unwinding. The skein is now mounted on the swift 15, whereupon all the members 23 will be moved towards the axis of the hub 16, thereby causing a pull in the elements 22'', which in turn will cause elements 22' to hug or squeeze the tubular elements to the spokes 16 and 17 respectively, which hugging action alone is sufficient to accomplish the fixation of the

position of said tubular members 21, and further the members 21 are stretched in such a manner that their openings 21' nearest the free ends of the spokes of the swift are enlarged or elongated along one axis to form a sort of spout-like formation indicated by the numerals 24, whereby said members 21 pinch the spokes at 24' which is the base of said spout 24. It is to be noted that such pinching action as occurs at points 24' in the manner described, is alone sufficient to secure the position of the members 21 along the spoke it is on. However, I have chosen to show an embodiment which utilizes all of said gripping actions, in order to teach an extremely efficient gripping means and to illustrate the complete teachings of this invention. It is evident that the amount of stretch in the members 21 when in tensed condition as shown in Fig. 6, will determine the tension in the skein 26, and said skein will remain taut automatically for the slack therein will be taken up as the spout dimension diminishes, meaning angle α diminishes. The greater angle α is initially, the greater will the tension be in the skein 26, and in the gripping forces action on the spokes heretofore explained.

When elements 22" are elastic, the automatic maintenance of tautness in the skein 26, is longer effective than when said elements are of non-stretchable material.

This invention is capable of numerous forms and various applications without departing from the essential features herein disclosed. It is therefore intended and desired that the embodiment herein described be deemed illustrative of the teachings of this invention and not restrictive and that the patent shall cover all patentable novelty herein disclosed; reference being had to the following claims rather than to the specific construction herein to indicate the scope of this invention.

I claim:

1. In combination, a swift having a hub and a pair of spaced opposite spokes extending radially therefrom, an elastic tubular member slidably mounted about one of the spokes, a bridge adapted to receive a skein thereon, having an element embracing the tubular member in a surrounding manner about said first spoke, and means to connect said bridge to the second spoke, whereby upon pulling said bridge towards the hub, said element will squeeze said tubular member against the spoke it is mounted on, thereby securing said tubular member at its position on said spoke.

2. In combination, a swift having a hub and a pair of spaced opposite spokes extending radially therefrom, an elastic tubular member slidably mounted about one of the spokes, a second elastic tubular member slidably mounted about the second of said spokes, and a bridge adapted to receive a skein thereon, having an element embracing the first tubular member in a surrounding manner about the first spoke, and a second element embracing the second tubular member in a surrounding manner about the second spoke, whereby upon pulling the bridge towards the hub, said elements will respectively squeeze said tubular members against the respective spokes, thereby securing said tubular members at their respective positions on the spokes.

3. The combination as defined in claim 1, wherein the bridge extends from and engages a region of the end of the elastic tubular member farthest from the hub, whereby upon pulling the bridge towards the hub, said end of the tubular member will be stretched more than any other

part of said member, forming a spout-like opening in said tubular member, whereupon said tubular member will pinch the spoke it is mounted on at the base of said spout-like formation, thereby further securing said tubular member at its position on the spoke.

4. The combination as defined in claim 2, wherein the bridge extends from and engages a region of the ends of each of the tubular members, farthest from the hub, whereby upon pulling the bridge towards the hub, said ends of the respective tubular members will be stretched more than any other parts respectively of said members, forming a spout-like opening in each of said tubular members, whereupon said tubular members will pinch the respective spokes on which they are mounted at the bases of said spout-like formations, thereby further securing said tubular members at their respective positions on the spokes.

5. In combination, a swift having a hub and a pair of spaced opposite spokes extending radially therefrom, an elastic tubular member slidably mounted about one of the spokes; said tubular member being provided with a hole in its wall, an element having a loop; said element being positioned within said tubular member and extending from one end thereof out of the bore in said tubular member, and said loop extending through said hole and positioned to encircle the body of said tubular member transverse the line of said first spoke, and a bridge element adapted to receive a skein thereon, connecting the extending end of said element and the second spoke; the end from which said first element extends of said tubular member being that farthest from the hub, whereby upon pulling said bridge towards the hub, the loop portion of said first element will squeeze said tubular member against the spoke it is mounted on, and the end of said tubular member from which said first element extends will be stretched forming a spout-like opening in said tubular member, whereupon said tubular member will pinch the spoke it is mounted on at the base of said spout-like formation, thereby securing said tubular member at its position on said spoke.

6. In combination, a swift having a hub and a pair of spaced opposite spokes extending radially therefrom, an elastic tubular member slidably mounted about one of the spokes, a second elastic tubular member slidably mounted about the second of said spokes; a pair of elements having loops; each of said tubular members being provided with a hole in their respective walls in substantially opposite relation; said elements being positioned, one within each of said tubular members and extending from one end thereof respectively out of the respective bores in said tubular members, and said loops extending respectively through said holes and positioned to encircle the respective bodies of said tubular members transverse the respective lines of their related spokes, and a bridge element adapted to receive a skein thereon, connecting the extending ends of said pair of elements; the ends from which said pair of elements extend from said tubular members being those farthest from the hub, whereby upon pulling said bridge towards the hub, the loop portions of said pair of elements will squeeze the respective tubular members against the spokes they are mounted on, and the ends of said tubular members from which said pair of elements extend will be stretched forming a spout-like opening in each of said tubular members, whereupon said tubular members will pinch

the respective spokes on which they are mounted at the bases of the respective spout-like formations, thereby securing said tubular members at their respective positions on the spokes.

7. A combination as defined in claim 5, wherein the loop portion of the element encircling the body of the tubular member is elastic.

8. A combination as defined in claim 5, wherein in the portion of the element extending from the bore in the tubular member is elastic.

9. A combination as defined in claim 6, wherein in the loop portions of the elements encircling the body of the tubular members are elastic.

10. A combination as defined in claim 6, wherein in the portions of the elements extending from the bores of the respective tubular members are elastic.

MORRIS W. BECKER.
